UNITED STATES PATENT OFFICE.

GEORGE K. COOKE, OF LONDON, ENGLAND.

HAND-STAMP.

SPECIFICATION forming part of Letters Patent No. 224,395, dated February 10, 1880.

Application filed April 19, 1879. Patented in England, November 23, 1878.

To all whom it may concern:

Be it known that I, GEORGE KISSAM COOKE, of the city of London, England, have invented a new and useful improvement in or applicable to dating and other stamp mechanism or device, and in flexible high type to be used therewith, for which Letters Patent were granted me in Great Britain, dated the 23d of November, 1878, and numbered 4,773 of said year, and

10 my invention is particularly described and ascertained in and by the following specification, reference being had to the accompanying drawings, and to the figures and letters marked thereon—that is to say:

15 This invention relates to improvement on dating and other hand stamp mechanism or device wherein it is requisite to change the date, number, or device by means of adjustable flexible type constructed or formed of india-rubber or other flexible material arranged in a suitable frame, the object being to conveniently and accurately adjust the type for stamping or printing either separately or in connection with a fixed flexible or other stereotyped die.

25 My improvement particularly consists in the combination, with one or more adjustable series of high types, constructed of rubber or other flexible material, of a guide-plate formed 30 with a beveled slot fitting the said types, so as to justify the same accurately in line with each other, or in the required correspondence with marks or characters on a fixed plate, with which said adjustable types may be used, as 35 hereinafter set forth.

In carrying my invention into practice I construct adjustable flexible type, of india-rubber or other flexible material, of such height that the same may be entered into or 40 through a conical or beveled slot in a guide-plate, so as to project through the same. The said slot, at its outer face or opening, corresponds in width with the thickness of the body of the adjustable flexible type or types, which 45 said type or types is or are so held in position by the said conically-slotted guide-plate that they remain in a direct straight line at right angles to the surface of the slotted guide-plate, the slot whereof acts as a "justifier" of the line 50 of types, such as, for instance, the figures and letters indicating a date, so that the types will,

when held in such position, give off a perfect impression not only of the said type or types, but also of any letters or figures which in the form of a stereotyped die surround the slot 55 and adjusted type or types, and are secured upon the outer surface of the slotted guide-plate, the printing-surface of said die being on a plane with the printing-surface of the adjustable type.

The improved flexible high type which I have invented consists of solid blocks, upon the upper face of which is formed the figure, letter, or device—*i.e.*, the type—and which said blocks are joined or connected together at 60 their base by an endless flexible band or strip; or such types may be placed in a groove in the bottom of the stamp-frame above the slotted guide-plate, said types having two, three, four, or more faces, and connected together at their 65 base to form double-faced blocks or clusters of types, presenting an appearance similar to the spokes of a carriage-wheel, and a central hole equivalent to the axle-hole in the hub of a wheel will be arranged centrally through the 70 block, joining the types together, and equidistant from the face of the type to admit of a pin or axle attached to the inner frame of the stamp, and around which pin the desired figures, numbers, or expressions may be rotated 75 into position for entering the slotted guide-plate. Again, types similarly constructed to those already described, but without the central opening, may be secured by being slipped in sideways in a slot in the type-carrying frame, 80 which will also allow that the flexible types may be conveniently removed and other requisite numbers, letters, or figures, or expressions be replaced in position for entering the 85 conically-slotted guide-plate.

In the drawings, Figure 1 is a side elevation of dating-stamp fitted with the continuous bands of high type constructed according to this invention, and showing the slotted guide-plate open; Fig. 2, a central section at line α 90 of Fig. 1.

A is the main frame, with handle, cross-bar, side plates, cover, and rolls, upon which the bands of type are mounted and are free to be turned, all as clearly shown. At B on the 100 side frame are snugs, forming the ears of the hinge, for reception of the hinge-ear on the

slotted guide-plate C. D is the beveled or conically-shaped guide of the plate C, which is clearly shown in Fig. 2. E is a projection or ear raised on plate C, through a tapped hole 5 wherein works the locking-screw E'. When all are adjusted in position the end of screw E' engages with the indentation E² on side plate of frame. F represents the stereotyped die on the slotted guide-plate.

10 The arrangement of apparatus shown in Figs. 3 and 4 is somewhat similar, but modified for the reception of the clusters of types hereinbefore described, and illustrated in Fig. 5, which shows four arrangements of the said 15 types. In Fig. 3 the cover of the frame A is broken away for purpose of illustration, and at B' is hinged (in the snugs of hinge B) the pin or axle, upon which are mounted, according as required, the types as shown in Fig. 5.

20 The opposite side plate of the frame A is slotted vertically to receive the outer end of the type-carrier axle, and the locking screw-ear E of the slotted guide-plate C has an extension or shoulder at E³, which, when plate 25 C is adjusted, butts against the extremity of the type-axle and holds same firmly in its slot in the side frame.

The other letters in these figures indicate 30 corresponding parts to those described in Figs. 1 and 2.

35 In Sheet 2 of the drawings the improved band-type is shown mounted upon a carrying-frame telescoping in the side frame and in the handle of the stamp, said frame being acted upon by a spiral spring from above.

Fig. 6 is a side elevation of the apparatus with a set of the solid high type of the bands of types entered through the slotted guide-plate C and its surrounding stereotyped die 40 F, ready for use. Fig. 7 is an end view of Fig. 6, and Fig. 8 a transverse central section of said figure.

In Fig. 9 the telescoping inner type-carrying frame is shown drawn back against the spiral spring, so as to withdraw the high band-types from the justifying-slot of plate C, so as to leave the types free to be adjusted. When the frame is released the types previously adjusted in line will enter the slot of plate C, and the surfaces will be presented on 50 a plane with the face of the stereotyped die F, and the line of types will be justified by the slot.

In this arrangement the conically-slotted guide-plate C, instead of being hinged, as previously shown, is attached by screws or rivets B E to the lower extremities of the stamp-frame A, other parts corresponding to those previously described being marked with similar letters of reference.

60 The ever-present difficulty of adjusting and maintaining separate figures, letters, or expressions in a direct straight line one with the other, is in my device avoided by the conically-beveled slotted die-plate automatically adjusting the said type.

I claim—

A stamp constructed with one or more adjustable series of high types connected at their bases and capable of movement or flexure 70 relatively to the band or center by which they are connected, in combination with a beveled guide-plate adapted to automatically justify the type, substantially as set forth.

In testimony whereof I, the said GEORGE 75 KISSAM COOKE, have hereunto set my hand this 21st day of February, 1879.

GEO. K. COOKE.
